UNITED STATES PATENT OFFICE

GEORGE NAISMITH AND DONALD M. NAISMITH, OF PITTSBURGH, PENNSYLVANIA

FURNACE

Application filed December 19, 1927. Serial No. 241,015.

Our invention is an improvement in heating furnaces of the recuperative type particularly adapted to the heating of ingots and the like, within a soaking pit or chamber.

It has in view to provide a recuperative furnace construction in which the fuel gases are brought together in a common vertical mixing well or chamber for combination with pre-heated air and then introduced horizontally into a common mixing, combustion and delivery chamber, with resulting circulation through the heating chamber of the furnace. The combustion gases thus combined enter at one side of the heating chamber, pass across and down into and then upwardly therethrough and finally emerge from the heating chamber at the same side, above the inlet opening and then outwardly and down through the waste gas passages in the mass of recuperative checkerwork.

The construction has in view to provide in a furnace construction of such type, means for utilizing practically all of the waste heat for pre-heating of the incoming air in a direct, economical and effective manner; also to utilize the gases of combustion most effectively and directly inwardly, upwardly and outwardly through and within the heating chamber, and to provide a simple, economical and easily built and repaired furnace construction of the type involved.

In the drawings showing one preferred embodiment of the invention:

Fig. 1 is a longitudinal vertical section 35 through the furnace on the line I—I of Fig. 2, partly broken away at each end;

Fig. 2 is a horizontal sectional view on the line II—II of Fig. 1;

Fig. 3 is a vertical section on the line 40 III—III of Fig. 2;

Fig. 4 is a perspective view of one of the circulating refractory blocks.

The soaking pit or heating chamber 2 of the furnace is of generally rectangular construction within side walls 3—3 and outermost end walls 4—5.

The construction of the furnace is rectangular as shown, preferably of uniform width from end to end, providing continuous side walls, between which are located the ele-

vated heating chamber and the recuperative construction for pre-heating, combination, combustion and exhaust of the gases.

Inwardly beyond end wall 4, of the furnace chamber proper, is a main supporting an enclosing inner wall 6, beyond which the heating chamber 2 extends by a floor 7 carried on suitable framing 32, as will be readily understood.

Inwardly beyond inner end wall 6 is a transverse apertured partition wall 7', through which pre-heated gas and air pass into a common intervening vertical well or chamber 8. The latter extends upwardly from the bottom foundation to substantially the full height of wall 7' and leads over by horizontal extension 9 into the lower portion of heating furnace chamber 2, and across the full inner width thereof.

Wall 6 extends slightly above floor 7 in the manner of a bridge wall 10, over which the fuel gases in combustion pass, the wall being preferably beveled inwardly and downwardly to allow for the free passage of the expanding gases of combustion into the full lower body portion of the heating chamber.

The upper portion of well 8 is covered by a horizontal partition 11 laid across from one side to the other and separating the incoming gas and air passage 9, from the upper outgoing waste gas passage 12. Said passage or space 12 extends from the upper portion of the heating chamber 2, above incoming channel 9, outwardly along the full upper length of the furnace over to an opposite inner confining wall 13.

Said wall, with wall 7, and side walls 3, provide the checkerwork-containing recuperator chamber which occupies the full length and width between said walls, and from the bottom to the top, as shown in Fig. 1.

Waste gas passage 12 extends for the full length of the recuperator chamber and the additional distance over to the heating chamber 2, and is covered by an arched roof 14, confining the outgoing gases in their passage, as indicated.

Heating chamber 2 is covered by a suitable closing cover 15 of any suitable construction, adapted to be moved away for insertion and

removal of the ingots or other articles to be heated.

The recuperative chamber is filled with a body of pre-heating brick or tile 16, shown in detail in Fig. 4. These are of special construction, and are open from end to end by a horizontal circulating channel 17 for passage therethrough of either air or combustion gases, as they may be used.

10 Alternating rows of the blocks are laid up close together with the openings 17 forming continuous series in such a manner as to provide continuous horizontal air and gas circulating and heating passages. These register with similar inlet openings 18 in wall 13 and outlet openings 19 in wall 7.

15 The longitudinal openings thus provided are in bank arrangement both vertically and horizontally across the recuperating chamber area, alternating with series of vertically arranged open circulating passages for the downgoing waste gases.

20 A horizontal series of such gas heating openings 18—17—19 is provided in the upper portion of the recuperative chamber, and a similar series of such heating openings for gas is provided below an intervening flue partition 31.

25 The bricks 16 as shown are arranged in vertical rows, alternating with longitudinally arranged laterally spaced bricks for downward and outward circulation of waste gases, as shown in Fig. 2. The alternating single bricks between each continuous row of bricks leaves a series of intervening vertical circulating spaces 20 and the horizontal openings 17 of the single unit bricks for the outgoing waste gases towards the stack.

30 By such arrangement the incoming air passes through each continuous upper series of openings 17 to chamber 8, and is in intimate heating relationship with the outgoing waste gases, thereby becoming highly heated and ready for combination with the fuel gas in chamber 8.

35 Air is furnished to openings 18 for such circulation from a common supply chamber 21 to which air is furnished from the atmosphere by any suitable means, as a conduit 22.

40 Vertically below air chamber 21 and partition 31 is the gas supply chamber 23, to which gas is furnished from any source, for similar pre-heating through a similar series of horizontal channels 18—17—19, extending from one end of the recuperative chamber to the other, and into the lower portion of chamber 8, for combination with the upper incoming hot air.

45 The several horizontal series of bricks are spaced apart and maintained in supported position by transverse bridge strips or bars 24, spaced apart longitudinally in each tier to provide clearance openings corresponding to the vertical openings 20.

50 By such arrangement the series of contin-

uous down going waste gas conduits 20 are provided, with the communicating individual cross openings 17, so that all of the waste gases will pass downwardly and horizontally, arriving finally at the common outlet chamber 25 communicating by flue 26 with the stack.

55 Supporting arches 27 provide intervening channels 28 registering with and leading downwardly from the several circulation spaces 20, providing ample circulation clearance, as will be readily understood.

60 The incoming gas and air mixing chamber 8 is provided with a bottom collecting cavity 29 closed by a removable gate or wall 30 for removal of any accumulated cinders or other waste products of combustion.

65 The construction and manner of operation of our improved furnace will be readily understood and appreciated from the foregoing description.

70 The supply of air and gas are under the control of the operator by any suitable valve or gate mechanism, and the furnace may be operated continuously, avoiding the necessity of the usual reversal of circulation and with 90 resulting regularity of operation. The temperature may be continuously maintained to the desired degree, and the articles to be heated are exposed to the upwardly circulating gases within the closed chamber for any 95 desired time.

75 The heating chamber itself may be of any desired proportions, but for best results the incoming fuel gases in combustion first pass 100 downwardly toward the bottom, then up through the whole interior, and outwardly from a higher level, with thorough action on the contained units, as ingots, etc.

80 What we claim is:

85 1. A furnace having an outwardly enclosed heating chamber and provided with laterally continuous inlet and outlet ports for heating gases located at different levels on the inner side of said chamber to cause all of the gases to pass inwardly across the 110 hearth and then upwardly and outwardly through the chamber, and having a vertical mixing chamber communicating with incoming air and gas and with the inlet port leading to the heating chamber.

90 2. A furnace having an outwardly extending entirely enclosed heating chamber provided at its inner side with a lower laterally continuous inlet port and an upper laterally continuous outlet port for heating gases and a longitudinally extended waste gas passage of substantially the width of the chamber, said inlet and outlet ports to and from the heating chamber being above and below the 115 hearth and roof of the chamber respectively.

95 3. A furnace having an entirely enclosed heating chamber provided with a lower inlet port for incoming gases and an upper outlet port for outgoing gases on the inner side of the chamber, the lower port being above a 120

bottom wall and having oppositely disposed downwardly sloping faces.

4. A furnace having an enclosed heating chamber provided at its inner side with a lower inlet port, a vertically arranged mixing chamber extending downwardly therefrom, means providing channels for introducing air and gas to the mixing chamber, an upper outlet port leading inwardly from the heating chamber and having a waste gas passage extension, and means providing circulation of waste gases from the said waste gas passage outwardly and downwardly between the air and gas channels.
5. A furnace having an outer enclosed heating chamber provided at its inner side with a lower inlet port and an upper outlet port, a continuous vertical mixing chamber for preheated gas and air opening upwardly into the inlet port, and a recuperator having passageways leading to the mixing chamber for gases to be heated and intervening cross passageways leading from the outlet port for waste gases.
6. A furnace having an enclosed heating chamber provided at one side with a lower inlet port and an upper outlet port, a vertically arranged mixing chamber opening at the top to the lower inlet port, and a recuperator having individual horizontal passageways leading to the mixing chamber for gases to be heated and intervening vertical and horizontal passageways between said passageways leading from the outlet port for waste gases to a gas outlet conduit.
7. A furnace having an enclosed heating chamber provided at one side with a lower inlet port and an upper outlet port, a vertically arranged hot air and gas mixing chamber leading to the inlet port, an upper waste gas chamber leading from the outlet port, a lower waste gas outlet conduit, and a recuperator between the upper waste gas chamber and the lower outlet conduit having a series of individual horizontal air and gas passageways leading to the mixing chamber and intervening reverse circulation passages leading from the waste gas chamber to the gas outlet conduit.
- 50 In testimony whereof we hereunto affix our signatures.

GEORGE NAISMITH.
DONALD M. NAISMITH.
